[57] CLAIM

The ornamental design for an oil container, as shown and described.

DESCRIPTION

FIG. 1 is a perspective view of an oil container with the cover closed showing my new design;

FIG. 2 is a front elevational view thereof with the cover closed;

FIG. 3 is a right side view thereof with the cover closed, the left side being a mirror image thereof;

FIG. 4 is a rear elevational view thereof with the cover closed;

FIG. 5 is a top plan view thereof with the cover closed;

FIG. 6 is a bottom plan view thereof with the cover closed;

FIG. 7 is a top plan view thereof with the cover open;

FIG. 8 is a perspective view thereof with the cover open;

FIG. 9 is a partial perspective view thereof with the grating removed therefrom and showing the dipstick, removed from its housed position and being inserted therein;

FIG. 10 is a perspective view thereof shown with a 5-gallon container;

FIG. 11 is a perspective view thereof with the legs folded or removed therefrom for secure placement on a 55-gallon drum; and,

FIG. 12 is a view taken along line 12—12 of FIG. 7.

The broken-line showing of environmental structure in FIGS. 9, 10 and 11 is for illustrative purposes only and forms no part of the claimed design.
